SAFETY DEVICE

Filed March 8, 1927

UNITED STATES PATENT OFFICE

EDMUND J. VON HENKE, OF CHICAGO, ILLINOIS, ASSIGNOR TO AUTOMATIC SAFETY TRIP CORPORATION, OF CHICAGO, ILLINOIS, A CORPORATION OF ILLINOIS

SAFETY DEVICE

Application filed March 8, 1927. Serial No. 173,659.

My invention relates to safety devices and particularly to such devices for use in machines, such as punch presses and the like. Many efforts have been made heretofore to produce a device which would guarantee the removal of the operator's fingers from the danger zone while the press is operating, but such devices for one reason or another do not fulfill the guarantee. The device which I have described and which will be hereinafter claimed overcomes the objections of the devices heretofore in use and at the same time is a simple and inexpensive device and one not likely to get out of order.

My invention will be better understood by reading the following description taken in connection with the accompanying drawings, in which

Fig. 1 is a side view of a portion of the machine with certain parts in section; and

Fig. 2 is a front elevation of a portion of the machine showing my device attached thereto.

There are many forms of punch presses which differ from each other in detail, but all of them include the essential parts of a frame, a ram or punch member and means for reciprocating the punch member. I have shown a portion of the frame 1, a shaft 2 upon which a pulley or fly-wheel 3 is mounted, and a clutch mechanism for connecting the fly-wheel to the shaft, upon which it normally rotates freely, for the purpose of reciprocating the ram at desired times. This clutch member may be of any construction, but I have illustrated one well-known form now in general use which consists of a rotatable key 4 mounted in a suitable slot in the shaft 2 and adapted when rotated to connect the hub of the fly-wheel 3 to the shaft 2.

Normally the key 4 is held in the position shown in Fig. 1 against the action of the coil spring 5, by the tripping stop 9. One end of the spring 5 bears against a lever 6, which is connected with the key 4, and the other end bears against a stop 7 on a collar 8 fastened on the shaft 2. The lever 6 is held in the position shown in Fig. 1 by a tripping stop 9 which is held in position by a coil spring 10 having one end bearing against a stop 11 fixed on a rod 12 and the other end bearing

against a projection 13 on frame 1. When the parts are in the position shown in Fig. 1 the fly-wheel rotates freely on the shaft and the punch member remains stationary.

When it is desired to operate the ram or punch member, the tripping stop 9 is removed from engagement with the lever 6 and the spring 5 acts through the lever 6 to rotate the key 4 so as to connect the pulley with the shaft 2. This operation takes place when the operator desires to punch a piece of metal from a blank, or when he desires to perform some other operation with the machine. This operation is produced as follows:

Two push buttons 14 and 15 are connected in series in the circuit of an electromagnet 16 having an armature 17 which is connected with a link 18. The circuit of the magnet 16 extends from one side 19 of the supply line, through a switch 20, push button 14, push button 15, magnet 16, contacts 21, wires 22 to the other side 23 of the line.

When the magnet 16 is energized the link 18 is moved upwardly from the dotted line position to the full line position shown in Fig. 1. This movement of the link 18 rotates a member 24 around the pivot 25 and sets the toggle 26-27, the member 24 being connected to the members 26-27 at their point of connection to each other, rotating a member 28 in an anti-clockwise direction around the pivot 29 because of the connection of the end of 27 with 28. The setting of the toggle 26-27 in effect rigidly connects the member 28 with the operating member 30 which is pivoted to the frame of the machine at 31 which pivot is concentric with the pivotal connection between the link 18 and member 24. The fly-wheel 3 is provided with a pin or other suitable projection 32. Upon the upward movement of the link 18 the member 28 is moved upwardly to the position shown in full lines into the path of the pin 32 which upon the revolution of the fly-wheel engages the member 28 and rotates the same around the pivotal point 31. This rotation positively forces the arm 30 to rotate around the pivotal point 31 in a clockwise direction. This, in turn, causes a downward movement of the tripping stop 9 through the rod 33

which is connected with the stop 9. As soon as the pin 32 operates the arm 30 it is evident that the tripping stop 9 is removed from the lever 6, whereupon the clutch is engaged and the punch member or ram of the press is operated. Immediately upon the actuation of the tripping stop 9 the member 6 will move away from engagement therewith, but the spring 10 will cause the stop 9 to immediately move back into the path of the lever 6 and as soon as the shaft 2 has completed a single revolution the lever 6 will then engage the stop 9 and disengage the clutch whereupon the ram will come to a standstill. Upon the downward movement of the rod 33 the member 34 which is connected therewith will rotate the bell crank lever 35 in a clockwise direction and open the contacts 21. This bell crank will remain in the operated position because of the spring link connection 36. This operation opens the contacts 21 which are in series with the magnet 16 thereby de-energizing the magnet which, in turn, permits the link 18 to drop and break the toggle 26-27, whereupon the member 28 immediately moves to the dotted line position out of the path of the pin 32. The clutch will therefore remain disengaged and the press will not repeat. It will not be possible to again operate the ram of the press until the buttons 14 and 15 have been released and have moved back into engagement with the back contacts 37. This engagement of the push buttons of the back contacts establishes a circuit through a magnet 38 which closes the contacts 21 and at the same time moves the bell crank 35 to the position shown in Fig. 1. In order to again operate the ram of the press it becomes necessary for the operator to place his hands on the push buttons 14 and 15, respectively, since these two buttons are placed apart a distance sufficient to make it impossible to be operated with one hand.

From the foregoing it will be evident that the operator must press two buttons which will make it necessary for him to remove both hands from the danger zone of the ram and that he must hold his hands on these buttons until the ram has operated, otherwise the circuit of the magnet 16 will be interrupted whereupon the clutch would not be tripped. After the press is operated the circuit of the magnet is automatically opened by the opening of the contacts 21 and thereafter the press will not repeat even though the operator continues to hold his hands on the push buttons. The push buttons must be released in order to effect the closing of the contacts 21 and must be pressed again before the press can again operate.

Electromagnetic means have been suggested for use in this connection heretofore, but in such cases the magnet must be extremely heavy in order to provide a sufficient

amount of power to trip the press, the magnet in those cases having been arranged to act directly to trip the clutch. A magnet having a sufficient amount of power is inevitably sluggish in operation and in practice it often happens that this sluggishness prevents the re-setting of the press quickly enough to prevent the repeating of the operation by the ram. Such a repeat operation has frequently resulted in serious damage to the hands or fingers of the operator because at that time the operator would be either removing the results of the preceding operation or placing material into position to be acted upon by the press.

By utilizing the electromagnet means to operate the light toggle members only and in combination therewith utilizing the power of the fly-wheel to perform the tripping operation, the magnet 16 is very quick and the entire operation is therefore sensitive and dependable. The electromagnetic member of the mechanism performs very little work and may therefore be designed to operate quickly and dependably for the purpose of releasing or rendering effective an everpresent power of sufficient magnitude to operate the tripping mechanism without any uncertainty whatever.

In present devices lazy operators will at times wedge one of the buttons leaving it continuously in the "on" position so as to save effort of pressing both buttons each time, leaving one of his hands free and subject to accident. No such action is possible in my device as both buttons must be returned to back contacts 37 before magnet 16 can be made to perform another operation.

I have therefore devised means which secure maximum safety against damage to the operator and which at the same time are inexpensive and simple and easily operated and maintained in operating order. The many advantages resulting from my invention will be apparent to those skilled in the art.

I claim:

1. In an automatic press, the combination of a driving shaft, a fly-wheel, a ram operated from said shaft, a clutch through which said ram may be connected to said shaft, mechanical means whose operation to operative position depends upon the absence of both hands of the operator from the danger zone of said ram for interposing a clutch actuator in the path of said fly-wheel and means on the fly-wheel for directly actuating said last-mentioned means to trip the clutch.

2. In a press, the combination of a driving shaft, a fly-wheel, a ram, a clutch between said shaft and said ram and means for engaging said clutch comprising a lever, a projection on said fly-wheel, means for moving said lever into the path of said projection and means actuated through the engagement of

said projection with said lever to engage said clutch.

3. In a press, the combination of a driving shaft, a fly-wheel, a ram, a clutch between said shaft and said ram and means for engaging said clutch comprising a lever, a projection on said fly-wheel, requiring both hands of the operator for moving said lever into the path of said projection and means actuated through the engagement of said projection with said lever to engage said clutch.

4. Means for tripping the clutch of punch presses having a fly-wheel, comprising an actuator on the fly-wheel, a pivoted lever, an electromagnetic relay for moving said lever into the path of said actuator, means requiring both hands of the operator for energizing said relay and means controlled by said lever for tripping the clutch.

5. Means for tripping the clutch of punch presses having a fly-wheel, comprising an actuator on the fly-wheel, a pivoted lever, an electromagnetic relay for moving the lever into the path of said actuator, means requiring both hands of the operator for energizing said relay, means controlled by said lever for tripping the clutch, and means rendered effective upon the tripping of said clutch for preventing the repeating of said press.

6. Means for tripping the clutch of punch presses having a fly-wheel, comprising an actuator on the fly-wheel, a toggle controlled pivoted lever, a relay for setting the toggle to bring the lever in the path of the actuator and means controlled by the lever for tripping the clutch.

7. Means for tripping the clutch of punch presses having a fly-wheel, comprising an actuator on the fly-wheel, a toggle controlled pivoted lever, a relay for setting the toggle to bring the lever in the path of the actuator, means controlled by the lever for tripping the clutch, and means actuated upon the tripping of the clutch for preventing the press from repeating.

8. In a clutch tripping device for punch presses, the combination of a bell crank lever having one arm pivotally mounted, a toggle for rendering said arm rigid with respect to the other part of the bell crank, clutch tripping means actuated by one arm of said bell crank and means under the control of the operator for setting said toggle.

9. In a clutch tripping device for punch presses, the combination of a bell crank lever having one arm pivotally mounted, a toggle for rendering said arm rigid with respect to the other part of the bell crank, clutch tripping means actuated by one arm of said bell crank, means under the control of the operator for setting said toggle, and means on a constantly moving part of the press for rotating the bell crank to trip the clutch.

10. In a clutch tripping mechanism for punch presses, the combination of mechanical means for tripping the clutch and electromagnetic means for controlling said tripping means and comprising an electromagnet, two push buttons in series in the circuit of said magnet and sufficiently separated to require both hands of the operator to close the magnet circuit, contacts also in said magnet circuit, means operative upon the tripping of said clutch for opening said contacts and a magnetic relay for closing said contacts upon the release of said push buttons.

11. The combination of a rotatable wheel, means operably connectable with said wheel, a relay device actuated directly by said wheel for controlling the connection between said wheel and said means and means under the control of an operator for controlling said relay.

12. The combination of a rotatable wheel, means operatively connectable therewith, a clutch, mechanical means actuated by the wheel for controlling the clutch, and a relay device under the control of an operator for controlling said last-mentioned means.

13. In an automatic press, the combination of a driving shaft, a fly-wheel on said shaft, a ram driven from said shaft, a clutch between said shaft and ram, mechanical means operable directly by said fly-wheel for actuating said clutch, and a relay for controlling said clutch-operating means.

CERTIFICATE OF CORRECTION.

Patent No. 1,828,723.

Granted October 20, 1931, to

EDMUND J. von HENKE.

It is hereby certified that error appears in the printed specification of the above numbered patent requiring correction as follows: Page 3, line 88, claim 12, after the word "actuated" insert the word directly; and that the said Letters Patent should be read with this correction therein that the same may conform to the record of the case in the Patent Office.

Signed and sealed this 2nd day of February, A. D. 1932.
